DISPENSING HEAD FOR FROZEN CONDIMENTS

Charles Erickson and Erick Spellman,
New York, N. Y.

Application January 7, 1950, Serial No. 7,062

Term of patent 3½ years

(Cl. D67—2)

To all whom it may concern:

Be it known that we, Charles Erickson and Erick Spellman, both citizens of the United States of America, residing at New York, in the county of the Bronx and State of New York, have invented a new, original, and ornamental Design for a Dispensing Head for Frozen Condiment, of which the following is a specification, reference being had to the accompanying drawing, forming part thereof.

We claim:

The ornamental design for a dispensing head for frozen condiment, as shown.

CHARLES ERICKSON.
ERICK SPELLMAN.
